UNITED STATES PATENT OFFICE.

JOHN G. S. LINDHOLM, OF CHICAGO, ILLINOIS, ASSIGNOR TO ANDERS P. LINDHOLM,
OF CHICAGO, ILLINOIS.

METALLIC CROSS-ARM PIN.

1,171,127.

Specification of Letters Patent.

Patented Feb. 8, 1916.

Application filed November 19, 1914. Serial No. 872,939.

To all whom it may concern:

Be it known that I, JOHN G. S. LINDHOLM, a citizen of the United States, residing at Chicago, in the county of Cook 5 and State of Illinois, have invented certain new and useful Improvements in Metallic Cross-Arm Pins, of which the following is a specification.

My invention relates to improvements in 10 metallic "cross arm pins" for the support of frangible insulators, such as are commonly employed for exterior electric wiring.

Among the objects of my invention are 15 to provide for the construction of an insulator pin that will be cheap, simple and efficient; adapted to be made of sheet metal by simple forming operations; adapted to be used under a variety of conditions as to 20 the character of the support therefor; and arranged to coöperate with the insulator to insure adequate retention of the insulator against displacement or rattling, but without liability to fracture the insulator under 25 changing temperature or weather conditions.

In the drawings wherein I have illustrated several structures embodying features of my invention, Figure 1 is a vertical 30 section on line 1—1 of Fig. 2 showing a sheet metal cross-arm pin in association with an insulator and a cross arm, and, in dotted lines, showing its availability for connection with another form of support. Fig. 2 is a cross section on line 2—2 of Fig. 35 1 and Fig. 3 is a perspective view of one insulator-pin section. Fig. 4 shows in transverse section a modified structure embodying features of my invention. Fig. 5 is a 40 cross section thereof on line 5—5 of Fig. 4. Fig. 6 shows in side elevation the form of device illustrated in Fig. 4. Fig. 7 illustrates another modified structure embodying features of my invention, and Fig. 8 is a fragmentary detail in section on line 45 8—8 of Fig. 7.

In general I contemplate making the insulator pin of sheet metal in a plurality of generally-similar longitudinal sections such 50 as may readily be made by ordinary metal working machinery and adapted for assemblage back-to-back jointly to form the pin. These sections may conveniently be formed of metal grooved or channeled in cross section throughout, and generally shaped in U- 55

or V-form, so that throughout the insulator-receiving stem portion the radially trending fins or webs may be threaded on their edges to coöperate with the threaded interior of the insulator in an adequate number of vertical planes to support and position the insulator. These threaded stem portions, I contemplate, shall be normally resiliently separated somewhat at their backs so that when engaged by the glass insulator they exert a spring tension on the interior of the insulator, preventing rattling or displacement, and yet affording a yieldability that enables the threaded pin structure to "come and go" under the influence of temperature variations thereby to avoid fracturing the glass insulator. Further I contemplate that below the threaded stem portion of each pin structure the middle or body portion shall be expanded for strength and enlargement of the base area and shall lead into horizontal base shoulders that afford adequate bearing surface for support of the pin against tipping; and that anchorage means be provided in conjunction with said seating base portions so that the pin may readily be applied to cross arms or other supports. Preferably also, I provide means for uniting the sections at a bearing-point or spring fulcrum substantially at the point where the stem and body parts merge, and such bearing points at the backs of the grooved sections I make wide enough for firm, adequate contact. 90

In the specific constructions shown 10 indicates in general an insulator of well known form having an internally threaded tapering socket 10', and 11 represents in general the pin structure by which said insulator is to 95 be connected to the cross arm 12^a or other suitable support.

Referring to the construction shown in Fig. 1 the pin 11 is composed of two vertically separable members 12—12' which 100 may be, in substance, duplicates. Each said pin section as shown consists of a single piece of sheet metal bent to form a V-bar, having the two wings 13—13' preferably connected by a narrow, flat back 14, which is 105 preferably tapered to the disappearing point at its bottom end as indicated at 14'. The upper end of each section, forming a stem portion 15, has its edges corrugated as at 16 to form threads and below the stem 110

portion the wings are expanded into body portions 17 terminating at the lower end in horizontal seating surfaces 18 below which the wings extend in the form of integral attaching post members 19 that may be serrated at their edges as at 20 and tapered at the bottom as at 21. Apertures 22 to receive nails or other attaching devices may be made in the back portions 14 of the post 5 parts 19 of the structure. When two of these sections are assembled back to back and secured together they form the completed pin. Such union between two sections may be effected in various ways, but 10 preferably I form in each section, contiguous to the junction of the body portion and stem portion thereof an aperture 23 from which is struck out an attaching ear 24, the ears on the two members respectively being 15 united to the top and bottom edges of their apertures so that in assembling the ear of each member may pass through the aperture in the other and be upset to rivet the parts together. Additional connections may be 20 provided, as shown, at other points on the body or post. The structures are so formed that when the meeting parts of the two back walls are brought together the upper portions thereof local to the threaded stem 25 parts 15 are sprung apart somewhat, to an extent slightly greater than that indicated in Fig. 1, so that when the taper-socketed insulator is screwed on the stem it brings the two stem members together somewhat, 30 putting them under tension but leaving them free for still further yielding so that they may act resiliently to compensate for differences in expansion and contraction between the glass and metal under varying temperature 35 conditions.

It will be observed that with the construction as above described the post portion of the pin structure may be driven into an ordinary pin opening in a cross arm, or it 40 may, of course, be driven into the end of a post or into wood of comparatively low density, by direct hammering, like a spike; or the lower portions of its post structure may be pried apart below the lowest engaging hook 23, and the pin may be attached 45 to the roof peak of a house or other angular structure, the sheet metal being readily susceptible of being battered down with a hammer to lie flat at its lower edge, and the 50 opening 22 permitting the structure readily to be nailed to its support.

In Figs. 4 to 6 is shown a structure preferably made with a somewhat broader U-shaped channel, but with the two channel 55 formed members affording a tapering threaded stem portion 115 substantially as heretofore described. The body 117, however, may be formed by diverting the two channel members to give a wide base effect, 60 and then bringing them back toward each

other to afford the seating surface as at 118, the side flanges being preferably spread apart at the base as indicated at 118' in Fig. 4. At the center the two converging base members 118 may be deflected downward 70 and each shaped into semi-cylindrical shell-form as indicated at 119, thereby providing jointly a hollow cylindrical shell, with its side edges meeting, lugs 121 being provided on the bottom of the shell members adapted 75 to be upset on the under side of an aperture in the cross arm to prevent withdrawal of the cylindrical post portion of the pin. These two post portions fitted together into a receiving aperture firmly position the 80 structure, and their uniting action may be supplemented by a union of the back portions of the two sections at substantially the junction of the body and pin, by means of slots and ears 123 substantially as heretofore 85 described.

In the form of construction illustrated in Figs. 4 to 6 the breadth of the base 118, in a line transverse to the expected line of strain of the wires to be supported, is increased only by deflection of the side flanges of the U-shaped channel member, but as shown in Fig. 8 the breadth of the base in this direction may be increased, if desired, by gradually widening the back wall of the 90 channel, indicated as 214, throughout the body portion. Also it is often desirable to use a construction that may be attached to a cross arm with an ordinary bolt in lieu of an integral post member of the pin itself, 95 and this result I may attain, as indicated in Figs. 7 and 8, in advantageous fashion by utilizing a construction generally similar to that shown in Fig. 4 as to the structure of the stem and body portion, but having the 100 base formed by two overlapping members 218 and 218', the member 218 forming an integral continuation of the back wall of its section and the member 218' likewise constituting a continuation of its back wall but 105 preferably supplemented by wing portions 218'' that flank the opposing base part 218. Each base portion may have an aperture made therein to receive the bolt 219, the 110 apertures being preferably made rectangular, with the material from the aperture in the upper base member struck down to form ears 221 extending through the aperture in the subjacent base member, thereby uniting the 115 two base members. Further union between 120 said members may be effected by diverting the extremities of the members into ears 223 respectively bent in opposite directions, and each taking through a corresponding aperture in the opposed base member.

While I have herein described in some detail particular embodiments of my invention that are especially adapted to meet the somewhat varied requirements of practice, it will be understood by those skilled in the 125 130

art that my invention is shown in modified embodiments not with intent to limit it to the particular construction shown, but as illustrative of the fact that changes in detail may be made without departure from the spirit of my invention and within the scope of the appended claims.

Having thus described my invention, what I claim is:—

- 10 1. An insulator-pin comprising a plurality of channeled sections, each providing a body portion and a stem portion, said sections meeting back to back below the stem portions and separated at the tops of the stem sections.
- 15 2. An insulator-pin comprising a plurality of channeled sections, each providing a body portion and a stem portion, said sections joined back to back below the stem portions and separated at the tops of the stem sections; and means for securing said body portions fixedly to a support, whereby by the point of jointure acts as a fulcrum for resilient movement of the stem ends.
- 20 3. An insulator pin composed of sheet metal formed into similar vertical sections of channeled cross section, each providing a stem portion threaded on its web-edges, a broadened back portion at the lower end of
- 25 30 the stem portion, for mutual bearing of the sections back to back, and an enlarged base portion affording a horizontal seating surface.
- 35 4. An insulator pin composed of sheet metal formed into similar vertical sections of channeled cross section, each providing

a stem portion threaded on its web-edges, a broadened back portion at the lower end of the stem portion, for mutual bearing of the sections back to back, an enlarged base portion affording a horizontal seating surface and integral means for connection of the back portions of said sections.

5. An insulator pin comprising a plurality of channeled sections, each providing a body portion and a stem portion threaded on its web-edges, said sections being positioned back to back, and means for connecting the channel backs together.

6. An insulator pin comprising two longitudinal sections, each providing a threaded stem portion, an enlarged base portion having a horizontal seating surface, a hole-engaging post portion, said sections meeting back to back below the upper ends of the stem portions, and the upper extremities of said stem portions being resiliently separated.

7. In an insulator pin, the combination of two channeled, sheet metal sections providing stem portions formed with diverging webs threaded at their edges, base portions having horizontal seating surfaces, and integral post-members.

In testimony whereof I hereunto set my hand in the presence of two subscribing witnesses.

JOHN G. S. LINDHOLM.
